UNITED STATES PATENT OFFICE.

ALVIN L. PEPPER, OF NEW YORK, N. Y.

BASEBALL GAME.

1,412,960.

Specification of Letters Patent. Patented Apr. 18, 1922.

Application filed April 1, 1921. Serial No. 457,667.

To all whom it may concern:

Be it known that I, ALVIN L. PEPPER, citizen of the United States of America, residing at New York, in the county of New York and State of New York, have invented 5 certain new and useful Improvements in Baseball Games, of which the following is a specification.

My invention relates to an improved game 10 apparatus and has for its object to provide an apparatus which will afford both to the player and spectator all the interest and excitement of a real game of base ball.

Other and further objects and advantages 15 of my invention will be in part described and in part apparent as the specification is proceeded with.

In the accompanying drawings forming part of this specification:

20 Figure 1 is a plan view of the invention: Figure 2 is a plan view of one of the marker rings.

25 Referring more particularly to the drawings, 5 denotes a board or frame of any suitable sheet material such as card board or the like upon the face of which is the field 6. The field contains a diamond 7 and out field 8 within the confines of a raised border or beading 9 provided with a rubber cushion 30 11 on its inner face for a purpose which will be presently described.

35 Arranged upon and about the diamond 7 and outfield 8 are a number of small circles or circular spaces 9 containing printed matter descriptive of the various plays which take place in an actual game of base ball. Each one of these spaces representing the various plays is provided with a hook, preferably located at the upper edge of the 40 circles or spaces as indicated at 10.

45 In practice the board 5 is either used as a parlor game or out of doors game. When used as a parlor game the hooks 10 are removed and the board is laid flat upon the floor or other convenient support such as a table (not shown) and the players, two or more of whom can play the game, each player representing a ball team, are provided with a rubber ring 12 of a size approximating that of the circular spaces 9 and preferably white in color. The player slides the rubber ring 12 across the face of the board causing the latter to strike against

the cushion 11, the object being to cause the ring on rebound to catch upon or "ring" 55 one of the circular spaces 9 representing a safe or scoring play. If a point for or against the player is made a colored marker ring 13, preferably red in color, is substituted for the white ring 12, so that the various plays may be readily followed. The player continues to throw the ring 12 until he receives three "outs", whereupon his opponent throws the ring. This play is continued for nine innings as in a regular game 65 of base ball, the score at the end of each inning being chalked up on any suitable score board (not shown).

When the game is played out of doors the board is preferably placed in upright position with the hooks 10 in place and the players throw the rings 12 from an imaginary line about ten feet distant therefrom. The only difference in the method of playing 70 from that followed when the board is placed 75 in a horizontal position is that the player instead of throwing the ring 12 against the cushion 11, throws the former directly at the hooks 10.

It will of course be understood that while 80 the game as played with the board in an upright position is more adaptable for out of doors use, the same can be readily played indoors.

Having thus described my invention: 85

What I claim is:

A game apparatus comprising a rectangular board representing a base-ball field, said board being adapted to be used in either a horizontal or a vertical position, said board 90 formed with a raised border on its front face, having a resilient portion at one end of the board, said field bearing circles representing different plays, hooks associated with said circles, and a rubber ring separate 95 from said board, whereby said ring is adapted to rebound and engage one of said circles when projected horizontally across said board against said cushion and thereby denote the play made by the player projecting 100 the ring, said hooks being adapted to catch said ring when said board is used in a vertical position and said ring is thrown towards said board.

In testimony whereof I affix my signature. 105
ALVIN L. PEPPER.
